United States Patent Office

Des. 198,122
Patented May 5, 1964

198,122

WATER CLOSET

John H. Whitehouse, Suffield, Conn., assignor to North & Judd Manufacturing Company, New Britain, Conn.,
a corporation of Connecticut

Filed May 16, 1962, Ser. No. 70,169

Term of patent 3½ years

(Cl. D4—5)

Fig. 1

Fig. 2

Fig. 3.

FIG. 3 is an elevational view taken from the opposite side of FIG. 2; and

FIG. 4 is a top plan view thereof.

I claim:

The ornamental design for a water closet, as shown.
